MANUAL CARD PUNCH APPARATUS

Peter P. Klepa, Los Angeles, Calif., assignor to
Data Entry Systems

Filed Oct. 9, 1973, Ser. No. 404,402

Term of patent 14 years

Int. Cl. D14—02

U.S. Cl. D26—5 C

Fig. 1

Fig. 2

Fig. 3

Fig. 4

FIG. 1 is a perspective view of a manual card punch apparatus illustrating the new design;

FIG. 2 is a front view thereof;

FIG. 3 is a rear view thereof; and

FIG. 4 is a side elevation view thereof.

The broken lines in FIG. 1 showing cards loaded in the invented manual card punch apparatus are for illustrative purposes only and form no part of the claimed design.

I claim:

The ornamental design for a manual card punch apparatus, substantially as shown and described.
